UNITED STATES PATENT OFFICE

PETER S. HARDY, OF NEW YORK, N. Y.

COMBINATION SHOWER BATH SPRAY, BATH SPONGE, AND MASSAGE DEVICE

Application filed February 28, 1930. Serial No. 432,130.

This invention relates to a combination shower bath spray, bath sponge and massage device.

The primary object of the invention resides in a combination bath appliance for attachment to the faucet of a water supply system for producing a shower spray, and to which attachment may be connected to adapt the appliance as a rubbing sponge, or a water driven massage device. The device is especially adapted for use in the bath and is intended to permit a user to stimulate the tissues of the body by a massaging action which tends to open the pores of the skin to allow thorough cleansing of the same not otherwise possible by the usual bathing method.

Another object of the invention is to provide a bath appliance in which the rotor is mounted within a shower head, there being valve means selectively operable to direct the flow of water so as to impart rotation to the rotor for actuating the same when the massage attachment is to be used, and for allowing the water to flow through the outlet opening in the shower head when desired, and means for facilitating the return flow of water from the shower head to a suitable outlet when the valve means are set to actuate the rotor.

Another object of the invention is the provision of a combination bath appliance which is simple of construction, inexpensive of manufacture and simple of operation.

With these and other objects in view the invention resides in the certain novel construction, combination and arrangement of parts, the essential features of which are hereinafter fully described, are particularly pointed out in the appended claims, and are illustrated in the accompanying drawings, in which:

Figure 1 is an elevational view showing my improved bath appliance connected to a faucet and illustrating the sponge attachment in use.

Figure 2 is a side elevational view of the head end of the device.

Figure 3 is a top plan view of the same.

Figure 4 is a horizontal sectional view on the line 4—4 of Figure 5.

Figure 5 is an enlarged vertical sectional view on the line 5—5 of Figure 3.

Figure 6 is a horizontal sectional view on the line 6—6 of Figure 5.

Figure 7 is a detail side elevational view of the massage elements per se.

Referring to the drawings by reference characters, the numeral 10 designates an elongated tubular handle member through which a pipe 11 extends, the opposite ends of the pipe extending beyond the ends of the tubular handle member for a purpose to be described. The outer extending end of the pipe 11 is screw threaded for threadedly receiving one end of an elbow fitting 12, the opposite end of the fitting being provided with outwardly extending ears or flanges 13 for seating engagement against the casing 14 of a shower head 15. Fastening elements in the nature of screws 16 pass through the ears or flanges 13 and into the casing for connecting the said casing to the elbow 12. The opposite extending end of the pipe 11 receives one end of an outer flexible hose or tube 17, the other end of the hose 17 fitting over a nipple 18 provided on a faucet attachment or coupling member 19. The coupling member 19 comprises a right angularly shaped casing 20 having a rubber nipple or collar 21 secured therein at its attachment end for fitting upon the spout of a faucet, while depending from the horizontal leg of the fitting is an outlet nipple 22. Seated within the horizontal leg of the casing 20 is a tube coupling member 23 provided with a reduced nipple 24 and which coupling member is removably associated with the casing and held in position therein by a set screw 25.

Fitting onto the nipple 24 of the coupling member 23 is one end of an inner flexible tube or hose 26, the same being of a smaller diameter than the outer hose 17 to provide a space between the exterior wall of the inner tube and the interior wall of the outer tube. The opposite end of the inner tube 26 is connected to the inlet passage 27 provided in the shower head casing 14, while the space provided between the inner tubing and

the outer tube has communication with an outlet fork or passage 28 also provided in the casing 14. From the description thus far, it will be seen that one end of the inner tube 26 is in communication with the inlet of the attachment fitting 19 and its opposite end connected to the inlet of the casing 14, while the space between the inner and outer tube constitutes a return passage which communicates with the outlet nipple 22 and the outlet passage 28 hereinbefore mentioned.

Fixed within the casing 14 axially thereof is a tubular shaft 29 and rotatably mounted upon the shaft is a rotor element 30 which is of stepped formation in cross section as shown in Figure 5, the top of which is provided with radially extending vanes or wings 31 disposed within a circular chamber 32 with which the inlet passage 27 and the outlet passage 28 communicates. The inlet passage 27 enters the side wall of the chamber, while the outlet passage 28 enters the top of the said chamber. A retaining nut 33 is threaded to the free end of the tubular shaft 29 for maintaining the rotor member 30 in engagement with the bearing surfaces provided on the inside of the casing 14. Suitable rubber packing 34 is provided between the rotor and the bearing surfaces of the casing for preventing any leakage of water through the several joints. The rotor is hollow of construction and includes a concavo convex plate 35 having openings or perforations 36 therein through which water is adapted to pass when the device is to be used as a shower bath spray. The interior of the plate 35 centrally thereof is curved inwardly to provide a conical enlargement or boss 50 in which a threaded socket 38' is provided. The socket opening onto the outer surface of the plate. The apex of the conical enlargement is disposed in axial alignment with the tubular shaft 29 so that water passing down through the tubular shaft will strike the curved wall and be deflected outwardly in all directions to pass through the holes or perforations 36 in the plate 35 when the device is used for a shower. The peripheral edge of the plate 35 constitutes a flange 37 for facilitating the attachment of a rubber sponge element 38, the said element being substantially cup shaped and provided with an inturned flange 39 for engagement with the flange 37 of the rotor. The sponge attachment 38 being constructed of a porous material, permits water to pass therethrough and which serves as a rubbing element during thorough washing or cleansing of the body. The rubber sponge being of a distendable material, the same may be stretched to enable the flange 39 to engage the flange 37 when applying the sponge attachment to the shower head, or to allow the walls of the sponge element to be expanded for the removal of the said element. The inlet passage 27 is provided with a conical valve

seat 40 with which a valve 41 coacts for opening and shutting off the supply of water from the inlet tube 26 to the chamber 32 and which valve 41 is carried on the inner end of a threaded valve stem 42 turnably mounted in a gland 43.

Leading from the inlet 27 is a passage or by-pass 44 provided in the casing 14 and which leads toward the axial center of the casing for communication with the tubular shaft 29. The inner end of the by-pass 44 terminates in a valve seat 45 with which a valve 46 coacts, the latter being carried at the inner end of a threaded valve stem 47, threaded in a packing gland 48. In the several figures of the drawings the valve 41 is shown in an open position to permit the flow of water from the tube 26 to the chamber 32 and thence out through the outlet 28 to the discharge passage between the outer and inner tubes 17 and 26, then to the outlet nipple 22. When the valve 41 is in an open position, the valve 46 is closed so that the water from the source of supply or faucet is directed to the chamber 32 and the force of the same causes rotation of the rotor 30 and at which time the massage element 48 shown in detail in Figure 7 and in dotted lines in Figure 5 is in attached position as illustrated in dotted lines in Figure 5. The massage element 48 is provided with a threaded stud 49 for threading in the threaded socket or recess 38' in the plate 35. It is of course understood that the sponge element 38 shown in Figure 5 is removed before the attachment of the massage element. During the use of the device as a massage apparatus, no water passes to the interior of the rotor, and therefore no spray is produced, as the force of the water is utilized as a power for imparting rotation to the rotor which in turn actuates the massage element 48.

When it is desired to utilize the apparatus as a bath shower or spray the valve 41 is closed on its seat 40 and the valve 46 opened so that the water flowing through the inner tube 26 passes through the by pass 44, thence through the tubular shaft 29 into the interior of the rotor, from which it passes through the opening 36 and produces a shower spray. It will therefore be seen that by the manipulation of the valves 41 and 46 the shower head may be selectively controlled so as to either produce a water shower or a water driven motor for the actuation of a massage element.

From the foregoing description it will be seen that I have provided a novel form of bath appliance which may be operatively connected up with the faucet of a bath tub and the device used for either a bath shower, a bath sponge, or a water driven massage device.

If desired, the valve 41 may be moved to an open position while the valve 46 is in a partially open position, sufficient to allow

water to pass through the shower head for rinsing purposes during a massage operation. Also the nipple 22 may be connected to one end of a hose leading to a drain other than the bath tub to prevent mixing of cold water used to actuate the rotor, with the hot water of a bath.

While I have shown and described what I deem to be the most desirable embodiment 10 of my invention, it is obvious that many of the details may be varied if desired, and I do not limit myself to the exact details herein shown and described, nor to anything less than the whole of my invention limited only 15 by the appended claims.

Having thus described the invention, what I claim as new and desire to secure by Letters Patent is:—

1. In a device of the class described, a 20 casing having an inlet and outlet, a rotor rotatably mounted in said casing, a massage element associated with said rotor, a faucet attachment fitting having an inlet and an outlet, an outer tube connecting the outlet 25 of said casing with the outlet of said fitting, and an inner tube arranged within said outer tube in spaced relation to the walls thereof and having its respective ends attached to the inlet of said casing, and the 30 inlet of said fitting.

2. In a device of the class described, a 35 casing having an inlet and outlet, a rotor rotatably mounted in said casing, a massage element associated with said rotor, a faucet attachment fitting having an inlet and an outlet, an outer tube connecting the outlet of 40 said casing with the outlet of said fitting, an inner tube arranged within said outer tube in spaced relation to the walls thereof and having its respective ends attached to the inlet of said casing, and the inlet of said fitting, and valve means in the inlet of said casing for regulating the flow of water thereto.

45 3. In a device of the class described, a casing, a hollow shower head rotatably mounted in said casing having outlet openings therein, radially disposed vanes provided on said shower head and arranged in 50 a chamber in said casing, a massage element associated with said shower head, a water inlet and a water outlet communicating with said chamber, the inlet also having communication with the interior of said hollow shower head, and valve means for selectively directing the inflow of water through 55 said inlet to either said chamber to actuate the rotor or to the interior of said shower head for discharge through said outlet opening.

60 4. A device of the class described comprising a tubular handle, a casing supported at one end of said handle, a water chamber within said casing having an inlet and an outlet 65 passage communicating therewith, a ro-

tor rotatably mounted within said casing and provided with radially arranged vanes disposed within said chamber, a massage element attached to said rotor, a water faucet attachment having an inlet and an outlet, 70 an outer flexible hose having one end fixed to the other end of said handle and its other end to the water faucet attachment in communication with the outlet therein, and an inner flexible tube enclosed within said outer flexible tube in spaced relation to the interior walls thereof, one end of said inner flexible tube being attached to the inlet of said faucet attachment and the other end to the inlet passage leading to said chamber, 75 the outlet passage to said chamber communicating with the space between said inner and outer tubes.

5. In a device of the class described, a casing having a water inlet and a water outlet, 80 a rotor member rotatably mounted in said casing and having a hollow perforated shower head, and valve means for selectively establishing communication between said inlet and said hollow head for the discharge 85 of water through the perforations therein, or for establishing communication between said water inlet and said water outlet through said casing for imparting rotation of said rotor member by reason of the water pressure 90 to operate a massage device adapted to 95 be connected to said rotor member.

In testimony whereof I affix my signature.

PETER S. HARDY.
